United States Patent Office.

FRANCIS ROACH, OF BOSTON, MASSACHUSETTS, ASSIGNOR TO HIMSELF
AND JOSEPH ZANE, OF SAME PLACE.

Letters Patent No. 71,790, dated December 3, 1867.

IMPROVEMENT IN BASIN-FAUCETS.

The Schedule referred to in these Letters Patent and making part of the same.

TO ALL PERSONS TO WHOM THESE PRESENTS MAY COME:

Be it known that I, FRANCIS ROACH, of Boston, of the county of Suffolk, and State of Massachusetts, have made a new and useful Invention Relating to Basin-Faucets; and do hereby declare the same to be fully described in the following specification, and represented in the accompanying drawing, which denotes a vertical section of a basin-faucet provided with my said invention.

The object of such invention is not only to construct a basin-faucet on the principle of the faucet invented by me, and described in Letters Patent, No. 55,784, granted to me and Joseph Zane, but so as to enable the main operative parts of the faucet to be easily raised out of its body, as occasion may require, for their disconnection or repair.

The main body or case of the faucet is shown at F as furnished with an induction-pipe, P, and a discharge-tube, L, and chambered in manner as represented, it being open at its upper end. Within the chamber, and extending around it, is a projection, n, having a female screw cut in its inner surface. A cap, H, fits upon the top or mouth of the body F, and has a tubular projection, R, extending down from it, and terminating in a valve-seat, i. The projection R has a small screw, o, to screw into and rest upon the part n, before mentioned. An inverted or bell-shaped valve-case, D, is screwed on the projection R, (as shown at X,) such case D being arranged within the body F. Holes e e are made through the sides of the case D; and there is arranged within the case a valve, A, provided with a stem, a, and a guide, b, arranged with respect to it in manner as represented. The valve is pressed up to the seat i by means of a helical spring, c, arranged within the case D, and resting upon the bottom of such case. A hole, r, for reception of the guide b, is made through the bottom of the case D. Furthermore, one or more openings, h h, are formed through the sides of the chamber projection R. A quick-threaded screw, G, is screwed into and through the cap H, such screw, at its lower end, being provided with a head, m, against which the top of the spindle a rests. The stem of the screw G passes through a stuffing-cap or box, I, screwed on the cap H, and such stem has a handle, K, fixed upon its upper end, the whole being arranged in manner as represented in the drawing.

By laying hold of the handle K and revolving the screw G, the valve A may be pressed off its seat, the elastic force of the spring c serving to return the valve to its seat, and to cause the screw G to revolve back after the hand may have been removed from the handle. When the valve is forced off its seat, the liquid, when in the body F, will pass through the holes e e, thence into the valve-case D, thence through the valve-seat into the chamber projection R, thence out of the latter through the holes h h, and thence into the upper part of the body F, and finally into and through the spout or pipe L.

Instead of a valve-case, D, screwed to the seat-projection R in manner as described, the spring c may be supported on a perforated partition extended across the body F, and having a hole made through it for reception of the guide b. I prefer, however, to have the valve-case D connected with the seat-case or extension R, as under such circumstances the former, with the valve and its spring, may be drawn out of the body with the seat-projection R.

I claim the combination and arrangement of the valve-seat case or the head-extension R and its cap H with the faucet-body F, the valve A, its operative screw G, and spring c.

I also claim the combination as well as the arrangement of the valve-case D with the valve-seat case R, its cap H, the faucet-body F, the valve A, its operative screw G, and spring c, the whole being constructed substantially in manner and so as to operate as specified.

FRANCIS ROACH.
